ATTORNEY

UNITED STATES PATENT OFFICE.

EDWIN BELMORE, OF PORTLAND, OREGON.

AUTOMOBILE TABLE.

Application filed May 2, 1921. Serial No. 465,952.

To all whom it may concern:

Be it known that I, EDWIN BELMORE, a citizen of the United States, and resident of Portland, in the county of Multnomah and 5 State of Oregon, have invented a new and useful Automobile Table, of which the following is a specification.

This invention relates more particularly to a collapsible table for automobile touring 10 purposes.

The object of my invention is to provide an exceedingly simple, light and strong table which can be readily set up or taken down, and which utilizes the running board 15 of the machine as a place of storage when traveling, a means for support when used as a table, and as a bench for the table on the car side.

I attain this result in the manner set forth 20 in the following specification and illustrated in the accompanying drawing, in which:

Figure 1 is a side elevation of this device. Figure 2 is a front elevation of Fig. 1 and 25 Figure 3 is a plan. Figure 4 is a perspective showing the device folded up into box form. Figure 5 is a detail showing hinge construction. Figure 6 is an enlarged detail showing 30 the manner of protecting the ends of the table boards. Figure 7 is a perspective view from the back of the folded table showing the manner in which it rests upon the running board.

Similar numbers of reference refer to the same or similar parts throughout the several 35 views.

Referring in detail to the drawing, I have constructed my device of four leaf members 10, 11, 12 and 13 which are hinged side by side by means of three rows of continuous 40 hinges 14. On the under side of the leaf 13 I have hinged the angular members 15 whose ends are hinged to the straps 16 firmly secured on the under side of the running board 17. A cottered pin 18 makes this connection removable when it is not desired to 45 carry the table on a car, or when it is desired to use it independently of an automobile.

Mounted on the ends of the leaf 12 are the 50 vertical ends 19 which are braced by means of the metal boxes 20 attached to the leaf 12 and the inner side of the end 19. These box portions 21 may be utilized as best seen fit by the owner. A hinged brace 22 limits 55 the movement between the leaves 12 and 13 to a straight line. The braces 22 are joined

to the leaf 13 by means of the standards 23 and to the members 19 by means of the ears 24 on the inner side of the members 19 to which they are secured by means of the bolts 60 25 which pass through the members 19, and also serve to secure the handles 26. A similar brace 27 limits the relation between the leaf 12 and the leaf 11 to a straight line.

On the under side of the leaf 11 are two 65 hinged legs 28 joined by means of the diagonal braces 29 to the rotatable hinges 30 on the under side of the leaf 13. A third brace 31 lends lateral stability to the table and is also attached by means of a rotatable hinge 70 32 to the leaf 11 and at its lower end provided with a hook 33 adapted to engage suitable holes in the legs 28. Similar hooks 33^A are attached to the lower ends of the braces 29 and form an easily removable connection 75 thereto.

A swivel arm 34 is also attached to the under side of the leaf 11 by means of a pivot 35 which also holds the clamping lever 36, whose use will be described latter. The 80 swivel arm 34 also forms a rest for the leaf 10 which is also provided with the perforated straps 37.

On the under side of the portion 15^A of the hinge 15 I have placed a rotatable key 39 85 adapted to lock the member 15 in a rigid relation to the member 15^A, by engaging the slot 15^C.

It will be seen that I have provided the edges of the boards with a metallic moulding 90 40 which is at once extremely rigid and easy to apply, and at the same time protecting the end grain of the wood against moisture.

It will be seen that various styles of hinges 95 may be employed for attaching the legs 28 or the braces 29 and 31 to the under side of the table top, without departing from the spirit of my invention.

In Figure 5 I have illustrated a hinge by 100 means of which the legs 28 are attached to the under side of the leaf 11. A metal clip 41 attached to the table leg 28 is hinged by the rivets 42 to an elongated base plate 43 rotatable on the pivot 44 which passes 105 through a slotted plate 45. The end 46 of the member 43 projects beyond the face of the leaf 11 and forms a support for the leaf 10. The slots 47 receive the sides of the clip 41 when the leg 28 is being folded against the 110 under side of the leaf 11.

It will be observed in Figure 4 that the

legs 28 and the brace 31 may be folded closely together against the member 34 and held in place against the now vertical leaf 11 by means of the clamp 36.

5 In Figure 7 it will be observed that the member 15 folds on top of the folded braces 29 which are held against rattling by means of the clamp 38.

10 The operation of my device is as follows: When desiring to carry this table on tours it is only necessary to place same on the running board, as shown in Fig. 4, and to insert the pins 18 and secure same with cotter pins.

15 In using my device as a table it is necessary only to disengage the members 37 from the portion 15^A of the hinge 15 and put the box into table form, as shown in Figures 1 to 3. The keys 39 are turned into a locked position, the braces 22 and 27 are moved into straight lines and the legs 28 are dropped to the ground. The braces 29 and 31 are then put into place and the supporting arm 34 turned at right angles to the table 20 leaves, and the table is ready for use.

25 It will be observed that the running board 17 is utilized as a seat for one side of the table, thereby rendering it necessary to carry only sufficient camp stools for the remaining 30 sides of the table. In event that it is desired to use the table in a tent or away from the machine it is only necessary to rest the leaf 13 upon stakes driven into the ground.

35 While I have thus illustrated and described my invention it is not my desire to limit myself to this precise form or method of application, but intend that it shall cover all forms and modifications that fall fairly within the appended claims.

40 What I claim as new is:

1. An automobile table consisting of four leaf members hinged together, end walls

erected on one of the center leaves, a pair of angular legs hinged at one end to the under side of the outside leaf which is hinged 45 to the end wall carrying leaf and at their lower ends to the running board of an automobile, and folding legs supporting the junction of the opposite side leaf and its adjacent leaf.

2. In an automobile table, the combination of four hinged leaves foldable in box form, a pair of angular legs hinged to one of said leaves and to the running board of a car, means for locking the upper portion of said 60 leg rigidly to said leaf, end walls formed on the leaf adjacent to said angular legs, folding braces hinged between said side walls and their adjacent leaves, a pair of folding legs under the leaves opposite the sides supported by said angular legs, and means for holding said legs in a vertical position.

3. In an automobile table, the combination of four hinged leaves foldable in box form with a pair of angular legs adapted to support the first of said leaves on the running board of an automobile, a pair of foldable legs supporting the third leaf and a rotatable locking hinge for each of said folding legs consisting of a plate having two parallel 75 slots, said plate being adapted to be secured to the under side of the third leaf, an elongated baseplate rotatably mounted on a pivot placed between said slots, a forked clip secured to the upper end of the table leg, said 80 clip having square ends pivotally joined to standards formed on said elongated plate in a manner that said squared ends may occupy said slots and permit the leg to swing or to cause the squared ends to rest firmly 85 against said slotted plate at right angles to said slots.

EDWIN BELMORE.
